UNITED STATES PATENT OFFICE.

WILLIAM S. HAMM, OF HUBBARD WOODS, ILLINOIS, ASSIGNOR TO THE ADAMS & WEST-LAKE COMPANY, OF CHICAGO, ILLINOIS, A CORPORATION OF ILLINOIS.

LANTERN.

947,037.

Specification of Letters Patent. Patented Jan. 18, 1910.

Application filed June 7, 1909. Serial No. 500,749.

To all whom it may concern:

Be it known that I, WILLIAM S. HAMM, a citizen of the United States, and resident of Hubbard Woods, county of Cook, and State 5 of Illinois, have invented certain new and useful Improvements in Lanterns, of which the following is a specification, and which are illustrated in the accompanying drawings, forming a part thereof.

10 The invention relates to lanterns in which there is employed a reflector, usually of glass, mounted upon the font.

The object of the invention is to provide a suitable support for the reflector which, 15 while securely holding it in position, will permit of its convenient insertion and removal.

The invention consists of a structure such as hereinafter described and illustrated in 20 the accompanying drawings, in which—

Figure 1 is a plan section of a lantern taken above the font and reflector; Fig. 2 is a rear elevation of the font and reflector; Fig. 3 is a side elevation of the font showing 25 a different form of reflector support; and Fig. 4 is a rear elevation of the device as shown in Fig. 3.

The lantern may take any desired form. The body of the lantern is conventionally 30 shown at 10, its light-emitting lens at 11, and its font at 12. The reflector 13 is shown as circular in form, and in the form of construction illustrated in Figs. 1 and 2 the reflector is supported on a pair of standards 35 rising from the font and is held in engagement with these standards by a spring arm engaging it above its horizontal diameter. As shown in Figs. 1 and 2, one of the supporting standards 14 is located on the vertical 40 diameter of the reflector, the other standard 15 being at one side thereof. Both standards are forked, as shown, with reference to the standard 14 at 16, 17, and with reference to the standard 15 as shown at 18, 45 19. In this form of construction the spring arm 20 also rises from the font and has its upper end forked, as shown at 21, 22, for receiving the edge of the reflector. Here the longer standard 15 serves to constitute the reflector at one side, while the spring arm 50 constitutes it at the opposite side and also bears it downwardly upon the two standards.

In the construction illustrated in Figs. 3 and 4, there is a pair of standards 23, 24, rising from the font at opposite sides of the vertical diameter of the reflector 13. Both standards are forked at their upper ends for receiving the edge of the reflector, and a spring arm 25 is shown as rising from the font on the vertical diameter of the reflector and bearing downwardly upon its upper edge, the upper end of the arm being given the forked form for better engagement with the reflector. In this instance the two supports serve to stay the reflector laterally, the office of the spring arm being to press it downwardly to its seat.

In both forms of construction the reflector may be inserted and removed by slightly 55 flexing the spring arm, and when in position is securely held. By mounting the reflector upon the font instead of securing it to the body of the lantern, as is the most common practice, all danger of relative displacement 60 of the lamp burner and reflector is removed.

There is not claimed herein broadly a reflector support comprising a bifurcated standard rising from the font of the lantern and a spring-arm for holding the reflector in 65 engagement with the support, for the reason that such claim is made in my copending application, Serial No. 350,022, filed December 29, 1906, in which the form of construction 70 herein described and specifically claimed is 75 shown.

I claim as my invention—

1. In combination, a lantern having a font, a reflector, a support for the reflector mounted on the font and comprising a pair of 80 forked standards, and a spring arm bearing downwardly on the reflector

2. In combination, a lantern having a font, a reflector, a support for the reflector comprising a plurality of forked standards rising from the font, two of such standards staying the reflector against lateral movement, one of such staying standards being a spring arm engaging the reflector above its horizontal diameter.

WILLIAM S. HAMM.
